UNITED STATES PATENT OFFICE

2,329,932

TOOL SUPPORT

Edward F. Nelson, Vallejo, Calif.

Original application May 31, 1940, Serial No. 338,179, now Patent No. 2,287,818, dated June 30, 1942. Divided and this application September 13, 1941, Serial No. 410,793.

10 Claims. (Cl. 248—125)

This invention relates to supports for holding an element, such as a tool, in a certain predetermined relation to another element such as the work to be operated upon the tool.

The disclosure of invention herein originally formed part of, and was divided from, my prior application, Serial No. 338,179, filed May 31, 1940, now Patent No. 2,287,818, dated June 30, 1942.

It is an object of the invention to provide a quick-acting support by means of which a tool may be rapidly positioned in operative relationship to the work to be operated upon.

Another object of the invention is to provide an improved clutch for securing together a pair of relatively adjustable members of a work support.

The invention possesses other objects and features of advantage which, together with the foregoing, will be specifically brought out in the detailed description of the invention hereunto annexed. It is to be understood that the invention is not to be limited to the specific form thereof herein shown and described as various other embodiments thereof may be employed within the scope of the appended claims.

Referring to the drawing:

Figure 1 is a vertical sectional view of the tool support of my invention. The tool carried by the support is shown in dotted lines and the base structure, upon which the tool support may rest and upon which the tool may operate, is also shown in vertical section.

Figure 2 is a transverse sectional view, to an enlarged scale, of the portion of the support lying in the plane indicated by the line 2—2 of Figure 1.

Figure 3 is a transverse sectional view of the portion of the support lying in the plane indicated by the line 3—3 of Figure 1.

In building construction, and in shipbuilding, where steel plates or bars are to be sheathed or overlaid with wood, it has been the practice heretofore to first position the wood over the steel substructure, drill holes through the wood and steel and then place in these drilled holes suitable bolts for permanently securing the wood to the steel. The placement or removal of such retaining bolts required the services of two workmen since one had to hold the bolt against turning from the underside of the substructure while the other, from above, applied and cinched the nut. Such procedure consumed considerable time and seriously slowed down production. Furthermore, if the wood was exposed to the weather, only a slight loosening of one or more of the

bolt nuts would permit water to seep through the bolt holes thus rusting the steel substructure or hastening rotting of the wood in contact with the steel. In later and improved construction a series of threaded studs were butt welded directly to the surface of the steel substructure thus eliminating the through bolt holes and dispensing with the services of the holder-on for securing the hold-down bolt against turning. This procedure however required that the wood overlay, after the hold-down studs were placed, be properly positioned over the studs, tapped so as to impress the ends of the studs into the underside of the wood, be removed and bored at the impressions to provide the stud apertures, and then be replaced on the studs. The hold-down nuts were then threaded on the studs thus securing the wood and the substructure together. This series of operations consumed nearly as much construction time as did the older through-bolt system. In my prior Patent No. 2,191,494, issued February 27, 1940, it is pointed out how considerable time can be saved in overlaying steel structures with wood or other covering material by first preforming in the covering the desired number of stud apertures, then placing the covering in its ultimate position on the steel substructure and then electrically butt welding the studs to the underlying steel through and concentrically of the apertures in the covering. Thus, immediately after the studs are welded in place, the hold-down nuts may be applied to the studs and tightened.

It is vitally important, since the weld which joins the stud to the steel substructure is being made in the bolt aperture and is therefore obscured from the view of the operator, that the distance the stud is drawn away from the steel, in creating the welding arc, be very accurately and uniformly maintained for each successive weld if uniformly strong unions are to be had between the studs and the steel substructure. In prior devices, the welding head, in which the stud forming one electrode of the welding circuit was held, was supported on a stand or tripod which rested on the upper surface of the wood overlay with the stud projecting downwardly into the stud aperture. Suitable stops on guides in the welding head permitted the stud, after contacting the surface of the steel substructure, to be drawn upwardly a predetermined distance so as to establish the arc gap between the end of the stud and the substructure. The adjustment of the support or tripod, when once set, did not require variation provided the thickness of the

wood overlay was uniform at the points where the successive welds were made. However, it has been found that the thickness of the wood varies considerably more or less so that the positioning of the end of the stud relative to the surface of the steel substructure also varies thereby causing variations in the arc gap and adversely affecting the quality of the resulting weld. I have provided a quick-acting support for such a welding head, or any vertical-feed rotary or reciprocating tool whose operation is to be started from a predetermined position relative to the work to be operated upon, which permits practically instantaneous adjustment of the starting position of the tool regardless of variations in the thickness of the wood overlay thus insuring that each weld or other operation is uniformly similar to the preceding one.

In detail, I have shown in Figure 1 a steel plate or structural bar 4 overlying which is a wooden plank or other such member 6 having an aperture 7 extending therethrough into which the threaded stud 8, which is to be butt-welded to the upper surface of the plate 4 may be inserted. A suitable shouldered nut, not shown, is adapted to be threadedly engaged with the upper end of the stud 8, after the latter has been welded in position concentrically of the aperture 7, for securing the wooden plank 6 and the plate 4 together. The plate 4 forms one electrode of the welding circuit while the stud 8 forms the other electrode thereof and it is the function of mechanism termed the welding head and generally indicated by the numeral 9 of Figure 1, to, first, hold the stud 8 in contact with the surface of the plate 4 until the welding current is turned on, secondly, to draw the stud away from the plate to create an arc gap, and thirdly, after the end of the stud and the confronting surface of the plate have been brought to the fusion point by the arc flame, to quickly join the melting members so as to effect a union thereof.

During the welding cycle the welding head 9, with the exception of the reciprocating ram 11 thereof and the stud 8, are rigidly supported in a fixed position. This is accomplished by a supporting structure comprising a base 12, which rests on the upper surface of the wooden overlay 6, having therein an opening 13, through which the stud 8 may be raised and lowered, and an upwardly rising tubular post 14 which is secured, at its lower end, to the base by a screw 16. Telescoping over and slidably axially of the post 14 is a tube 17 having thereon a pair of spaced brackets, each comprising a split collar 18 secured to the tube by means of a clamp screw 19 and having extensions 21 suitably formed to accommodate and engage the particular tool to be supported. A key 22, projecting through a suitable opening formed in and adjacent the lower end of the tube 17 and entering a keyway 23 cut longitudinally in the periphery of the post 14, serves to prevent relative rotation between the tube and post and thereby to maintain the tool or welding head 9 in axial concentricity with the base opening 13. The upper end of the tube 17 extends into a bored recess 24 formed in a hub 26 having a radially projecting grip 27, and the hub 26 is split axially of the recess 24 and provided with apertured lugs 28 bearing a clamp bolt 29 for clamping the tube 17 in the recess 24. The grip 27 provides a handle for the operator so that he may raise and lower the tool 9 with respect to the base 12.

Means is provided for securing the tool in a selected elevated position. Secured at its upper end in the recess 24, by the clamp bolt 29, and positioned within the tube 17, is a collet sleeve 31 which extends downwardly in axial concentricity with the tube 17, terminates adjacent the lower end of the latter, and telescopes within the post 14. The lower end of the collet sleeve is provided with a plurality of circumferentially spaced, axially extending slots 32, and with a tapered countersink 33 forming a continuation of the internal bore 34 of the sleeve. This construction provides a plurality of radially flexible fingers at the lower end of the collet sleeve. Positioned concentrically within the collet sleeve is a control rod 36 secured to the lower threaded end 37 of which is a frusto-conical plug 38 complementary with and engaged in the tapered countersink 33 of the collet sleeve. The upper end 39 of the control rod 36 passes slidably through a central aperture formed in a washer 41 which rests in a fixed position spaced from the upper end of the collet sleeve, against a shoulder formed within the bore of the collet sleeve. A nut 42 is threaded on the extreme upper end of the control rod 36 and interposed between the nut 42 and the washer 41 is an extension spring 43. The spring 43 is for the purpose of urging the control rod 36 upwardly in a direction axially of the collet sleeve 31 so as to draw the plug 38 into the countersink 33 thereby radially urging the flexible fingers of the collet sleeve into tight frictional engagement with the inner periphery of the post 14. This locks the movable tube 17 and the post 14 against relative longitudinal displacement and also holds the welding head 9, or other tool carried by the extension 21, firmly in the desired elevated position. In the event that a tool of considerable weight is being used, the peripheral surfaces of the fingers contacting the post 14 may be knurled so as to bite into the surface of the post and thereby obtain maximum grip between the engaged parts.

Means is provided for releasing the frictionally connected post 14 and tube 17, to permit raising and lowering of the tool 9, and means is further provided for partially counterbalancing the weight of the tool to lessen the force required to raise the latter. Positioned within the recess 24 and between the concentric tube 17 and collet sleeve 31, is a short tubular filler 44 and the assembled tubular members are each provided with aligned apertures which form, as shown in Figures 1 and 2, an opening 46 through which passes a release lever 47. A pin 48, having its opposite ends seated in holes drilled into the tube 17 and the filler tube 44, extends transversely across the opening 46 and through a journal aperture bored in the release lever so that the latter is pivotally mounted on the pin. The inner end of the release lever is bifurcated to provide a pair of fingers 49 which bear against a washer 51, secured to the control rod 36, and the outer end 52 of the release lever is extended substantially parallel to and outwardly substantially equal to the extent of the grip or handle 27. When the operator desires to raise or lower the tool 9, he extends one or more of the fingers of his hand resting on the grip 27 to engage the outer end 52 of the release lever and draws the said outer end of the lever towards the grip. This causes the fingers 49 to move the control rod 36 downwardly so as to move the plug 38 out of the countersink 33 thereby releasing the radial pres-

sure of the collet fingers against the inner wall of the post 14. With the base 12 maintained in contact with the surface of the wood overlay 8, the tube 17 and the various parts, including the tool 9, carried thereby may be shifted longitudinally of the post 14 to any desired position. Release of the lever extension 52 will again set the friction lock to secure the tool 9 in fixed relation to the base 12. An axially expansible spring 54, positioned within the tube 17 and interposed between the ends of the post 14 and the filler tube 44, respectively, serves, when the friction lock is released, to urge the tube 17 and its connected parts upwardly thereby partially counterbalancing the weight of the tool 9 and facilitating its vertical adjustment with greater ease.

As was stated above, a uniform arc gap should be maintained in successive welds if each weld is to possess the maximum of strength. As is fully described in my above-mentioned prior patent, the mechanism of the welding head 9 is pre-set so that the lower end of the stud 8 rests on the upper surface of the steel substructure 6. When the welding current is turned on, action takes place within the welding head, and while the latter is held rigidly fixed with relation to the steel substructure 4, which moves the stud 8 to a position elevated above the substructure 4 to create the arc gap between the stud and substructure 4. The length of this arc gap is usually only a small fraction of an inch and is chosen to produce the desired arc flame depending upon the amount of welding current available. It will be seen that if the distance between the upper surface of the substructure 4 and the overlying planking 6 is uniformly the same in each aperture 7 in which a stud 8 is to be placed, the welding of a large number of studs may be carried forward in the knowledge that the arc gap of each successive weld will be the same as that of the previous welds. However, due to variations in thickness of the planking 6 and the possibility of raised seams, protuberances or depressions in the surface of the substructure 4 happening to coincide with one or more of the apertures 7, the depths of all of the apertures will not be alike. Using previously known equipment, work was seriously retarded by the requirement that the workman, before making each weld, measure the depth of each hole and set the welding head support accordingly to provide the desired arc gap. With the support of my invention, it is only necessary to place the base 12 in position on the planking 6 over the aperture 7 and release the friction lock between the post 14 and the tube 17 so as to allow the stud 8 to descend into the aperture 11 until it just touches the upper surface of the substructure 4. The lock may be then re-engaged since the stud is now positioned to provide the correct length of arc gap when it is drawn away from the substructure by the lifting mechanism within the welding head. It will be therefore seen that a workman may quickly set the apparatus for each individual hole in which a stud is to be mounted without appreciably cutting down his production speed.

Having thus described my invention in detail, what I claim as new and desire to secure by Letters Patent is:

1. A tool support comprising an upper tubular section, means on said upper tubular section for connecting a tool thereto, a lower tubular section telescopically engaged with said upper tubular section and slidably axially thereof, a collet sleeve carried by said upper tubular section, said

collet sleeve being concentric with the upper tubular section and telescopically engaged with the lower tubular section, said collet sleeve, further, at its lower end, being provided with a tapered bore and a plurality of longitudinally extending slots circumferentially dividing the collet sleeve into a plurality of radially flexible fingers, a complementarily tapered plug in said tapered sleeve bore, a control rod connected with said plug and extending axially along said collet sleeve, pressure means interposed between said control rod and said collet sleeve for urging said control rod in one direction axially of the sleeve to press said plug into the said tapered bore of the sleeve and to expand said flexible fingers radially into engagement with said lower support section, manually operable means carried by said upper tubular section and connected with said control rod for urging the control rod in an opposite direction to radially contract said flexible fingers, and an apertured base on said lower support section for engaging a surface to support said tool in position above said surface.

2. A tool support comprising an upper tubular section, means on said upper tubular section for connecting a tool thereto, a lower tubular section telescopically engaged with said upper tubular section and slidably axially thereof, a collet sleeve carried by said upper tubular section, said collet sleeve being concentric with the upper tubular section and telescopically engaged with the lower tubular section, said collet sleeve, further, at its lower end, being provided with a tapered bore and a plurality of longitudinally extending slots circumferentially dividing the collet sleeve into a plurality of radially flexible fingers, a complementarily tapered plug in said tapered sleeve bore, a control rod connected with said plug and extending axially along said collet sleeve, pressure means interposed between said control rod and said collet sleeve for urging said control rod in one direction axially of the sleeve to press said plug into the said tapered bore of the sleeve and to expand said flexible fingers radially into engagement with said lower support section, a hand grip connected with and extending radially from said upper support section, a release lever pivotally mounted on said upper support section adjacent said hand grip and connected with and to move said control rod downwardly relative to the upper support section to move said tapered plug out of said tapered bore so as to radially contract said flexible fingers from engagement with said lower support section, and a base carried by the lower support section for engaging a surface so as to support said tool in position above said surface.

3. A tool support comprising upper and lower sections slidable one on the other, laterally extending means on the upper section for mounting a tool at the side thereof, means for locking the two sections together, a handle by which the support and attached tool may be carried disposed on one of the sections and extending laterally over the tool, a base disposed on the lower section, and means for releasing the locking means disposed adjacent the handle.

4. A tool support comprising upper and lower sections slidable one on the other, laterally extending means on the upper section for mounting a tool at the side thereof, means for locking the two sections together, a handle by which the support and attached tool may be carried disposed on one of the sections and extending laterally over the tool, a base disposed on the lower section, and a lever for releasing the locking means extending laterally from the upper

section above the tool and adjacent the handle.

5. A tool support comprising upper and lower sections slideable one on the other, means on the upper section for mounting a tool thereon, a spring interposed between the two sections to counterbalance the weight of the tool carrying section, means for locking the two sections together, a hand grip by which the support and attached tool may be carried disposed on one of the sections, a base disposed on the lower section, and digitally operated means adjacent the hand grip for releasing the locking means.

6. A tool support comprising a single tubular section, a second section comprising a pair of concentric spaced tubular members between which the single section is telescoped, a base fixed on one of the sections, a hand grip fixed on one of the sections, means on one of the sections for mounting a tool, spring pressed means for locking the two sections together, counterbalancing means for the tool carrying section interposed between the sections, and means for releasing the spring pressed locking means arranged adjacent the hand grip.

7. A tool support comprising a single tubular section, a second section comprising a pair of concentric spaced tubular members between which the single section is telescoped, a base fixed on one of the sections, a hand grip fixed on one of the sections, means on one of the sections for mounting a tool, spring pressed means for expanding the inner tubular member against the surrounding tubular section to lock the two sections together, a counterbalancing spring disposed between the concentric tubular members and interposed between them and the single tubular section, and a digitally operated lever

adjacent the hand grip for retracting the expanding means to release said lock.

5 8. A tool support comprising upper and lower sections slideable one on the other, means on one of the sections for attaching a tool on the side thereof, a hand grip by which the support and attached tool may be carried, said hand grip being fixed on the tool-holding section and extending laterally therefrom over the center of 10 gravity of the combined support and tool, a base arranged on the other section and extending laterally therefrom beyond said center of gravity, said base being recessed to permit passage therethrough of tool parts, spring pressed means for locking said sections together, and means adjacent the hand grip for releasing said locking means.

15 9. A tool support comprising upper and lower sections, a base fixed on the lower section, means on the upper section for mounting a tool, the upper section being slideable on the lower section to position part of the tool below the base, means for locking the two sections together, a hand grip by which the support and attached tool may be carried, and means for releasing the locking means disposed adjacent the hand grip.

20 10. A tool support comprising a lower tubular section, an upper tubular section slideable within the lower section, a base on the lower section, means for mounting a tool on the upper section, a hand grip on the upper section, a rod in the upper section and terminating in a conical plug arranged in the lower end of the upper section, a spring interposed between the rod and the upper section to draw the plug into the section to expand it against the outer section, and a digitally operated lever adjacent the hand grip for moving the rod to free the plug.

EDWARD F. NELSON.
